CLAIM

The ornamental design for a robotic arm, as shown and described.

DESCRIPTION

FIG. 1 is a top, front, right perspective view of a robotic arm; FIG. 2 is an enlarged view of portion 2 encircled in FIG. 1; FIG. 3 is an enlarged view of portion 3 encircled in FIG. 1; FIG. 4 is a right-side view of the robotic arm; FIG. 5 is an enlarged view of portion 5 encircled in FIG. 4; FIG. 6 is a left-side view of the robotic arm; FIG. 7 is an enlarged view of portion 7 encircled in FIG. 6; FIG. 8 is a rear view of the robotic arm; FIG. 9 is an enlarged view of portion 9 encircled in FIG. 8; FIG. 10 is a front view of the first embodiment; FIG. 11 is an enlarged view of portion 11 encircled in FIG. 10; FIG. 12 is an enlarged view of portion 12 encircled in FIG. 10; FIG. 13 is a top plan view of the first embodiment; FIG. 14 is an enlarged view of portion 14 encircled in FIG. 13; and, FIG. 15 is a bottom plan view of the robotic arm. The broken lines illustrate portions of the robotic arm and form no part of the claimed subject matter.

UNITED STATES PATENT AND TRADEMARK OFFICE
CERTIFICATE OF CORRECTION

PATENT NO. : D873,878 S
APPLICATION NO. : 29/634027
DATED : January 28, 2020
INVENTOR(S) : Frankie Vazquez et al.

Page 1 of 1

It is certified that error appears in the above-identified patent and that said Letters Patent is hereby corrected as shown below:

On the Title Page

Item (12), should read:

Vazquez et al.

Item (72), after inventor number one, insert:

-- Sebastien Messier, Fremont, CA (US);
Louis-Joseph Caron L'ecuyer, Blainville (CA);
Alexandre Picard, Saint-Colomban (CA); --

Signed and Sealed this
Twenty-second Day of July, 2025

Coke Morgan Stewart
Acting Director of the United States Patent and Trademark Office
